UNITED STATES PATENT OFFICE.

WILLIS W. KRUTSCH, OF COFFEYVILLE, KANSAS, ASSIGNOR OF ONE-EIGHTH TO MILES K. BARRON, OF COFFEYVILLE, KANSAS, ONE-FOURTH TO HERBERT HIGGINBOTTOM, OF CHERRYVALE, KANSAS, AND ONE-FOURTH TO JOHN W. CUNNINGHAM, OF COFFEYVILLE, KANSAS.

WEDGE-FORMING MACHINE.

No. 919,032.

Specification of Letters Patent. Patented April 20, 1909.

Application filed September 21, 1908. Serial No. 454,118.

To all whom it may concern:

Be it known that I, WILLIS W. KRUTSCH, a citizen of the United States, residing at Coffeyville, in the county of Montgomery and State of Kansas, have invented certain new and useful Improvements in Wedge-Forming Machines, of which the following is a specification.

My invention relates to improvements in wedge forming machines; and my object is to produce a machine of this character whereby wooden wedges may be rapidly and perfectly formed without waste of material. The machine is adjustable so that wedges of 15 different lengths may be produced on the same machine.

Referring now to the accompanying drawing, which illustrates the invention: Figure 1 represents a plan view of my machine. 20 Fig. 2 is a vertical longitudinal section on line II—II of Fig. 1. Fig. 3 is a broken inverted plan view of the machine. Fig. 4 is a broken section on the plane of line II—II of Fig. 1. Fig. 5 is a cross section on line V—V 25 of Fig. 2.

In carrying out the invention I employ a frame consisting of two longitudinal bars 1, which may be firmly secured to a base 2, or they may be secured directly upon a work-bench. 3 designates a cross-head reciprocably mounted in said frame, the sides thereof operating in grooves 4 in the lower portions of bars 1.

5 designates a gage carried by cross-head 3, it being adjustably secured thereto by bolts 6 and 7, so that its forward end may be raised or lowered, and thus regulate the length and thickness of the wedges to be produced. Gage 5 is provided at its upper portion with a shoulder 8 and at its lower portion with a transverse lug 9, which latter is seated in the bottom of a V-shaped groove 10 in the upper portion of the cross-head, so that the gage may rock therein while being 45 adjusted.

11 designates a transverse groove in the gage at the bottom of shoulder 8, adapted to receive the cutting edge of a blade 12, which is adjustably secured to the rear portion of 50 the frame by screws 13 14, so that its rear end may be tipped up sufficiently to clear the wedges as they are cut from a block.

The gage and the cross-head are actuated by a hand-lever 15 through a connecting-bar

16, pivotally secured at its ends to the gage 55 and the hand-lever.

In practice a block of wood is placed upon the inclined portion 17 of the gage with its rear end abutting against shoulder 8, as shown by dotted lines in Fig. 2. Lever 15 60 is then swung forward to carry the cross-head and the gage forward to push the block against blade 12, which cuts through the block in a horizontal plane, and thus forms a wedge 18, see Fig. 4. The rear side of 65 groove 11 is prevented from contacting with the cutting edge of the blade by the forward end of the cross-head, which contacts with the end of grooves 4.

From the above description it is apparent 70 that I have produced a simple machine whereby wedges may be quickly and cheaply produced, and while I have shown the preferred form of my invention, I, of course, reserve the right to make such changes as 75 properly fall within the spirit and scope of the invention.

Having thus described my invention, what I claim is:—

1. A wedge forming machine embodying a 80 frame, composed of a base, a pair of grooved longitudinal bars on said base, a cross head sliding in said grooves of the bars, said cross head being formed with a transverse V-shaped groove, a gage having a transverse 85 lug on its bottom which seats in said V-shaped groove, bolts secured to said cross head and said gage extending on opposite sides of said lug and groove thereof, said gage on its upper face being formed with a shoulder and a groove at the bottom of the shoulder, a cutting blade secured to said frame bars adapted to have its cutting edge extend in said last named groove of the gage, and means whereby the cross head may be operated. 95

2. A wedge forming machine embodying a frame, a cross head reciprocatingly mounted in the frame, said cross head being formed with a transverse groove on its upper face, a gage having a transverse lug on its bottom face which seats in said groove of the cross head so as to be capable of having a rocking movement therein, bolts secured to said gage and cross head extending on opposite sides 100 of said groove and lug, and a cutting blade on the frame. 105

3. A wedge forming machine embodying a

frame, a cross head mounted to reciprocate therein, a gage overlying said cross head, means disposed central of the length of said gage and cross head whereby the gage may have rocking movement with respect to the cross head, means on opposite sides of said first named means to secure said gage in its adjusted position against movement with respect to said cross head, a cutting blade, and means whereby said cross head may be reciprocated.

4. A wedge forming machine embodying a frame, formed with longitudinal grooves, a cross head for reciprocating movement in said grooves, a cutting blade secured to said frame, a gage on said cross head, said gage being formed with a shoulder and with a groove at the base of the shoulder into which the cutting edge of the blade is adapted to project, said cross head having one of its ends for engagement with the end walls formed by said longitudinal grooves of the frame at one

end of the latter to restrict the extent of projection of the cutting edge of the blade into said groove of the gage, and means whereby said cross head may be reciprocated.

5. A wedge forming machine embodying a frame, vertically adjustable screws carried by the frame, a cutting blade having its rear end on its bottom face seating on the upper ends of said screws, second screws which pass through said blade and into the frame, the cutting edge of said blade being supported at its ends by engagement with the frame, a cross head, a gage carried thereby, and means to impart reciprocating movement to said cross head.

In testimony whereof I affix my signature, in the presence of two witnesses.

WILLIS W. KRUTSCH.
